UNITED STATES PATENT OFFICE.

EUGENE W. CALDWELL, OF NEW YORK, N. Y.

PHOTOGRAPHIC DEVELOPING APPARATUS.

1,141,314.

Specification of Letters Patent.

Patented June 1, 1915.

Continuation of application Serial No. 838,448, filed May 14, 1914. This application filed December 19, 1914. Serial No. 878,010.

To all whom it may concern:

Be it known that I, EUGENE W. CALDWELL, a citizen of the United States, and resident of the city, county, and State of New York, have made a certain new and useful Invention Relating to Photographic Developing Apparatus, of which the following is a specification, taken in connection with the accompanying drawing, which forms part of 5 the same and this application is a continuation of my co-pending application 838,448, filed May 14, 1914, containing similar subject-matter.

This invention relates especially to apparatus for developing photographic negatives and comprises frames of celluloid or other suitable tough inert material in which the negatives are disengageably mounted so as to be properly supported in the developing tanks and in the drying apparatus and so forth.

The frames may comprise wide sides preferably at least several times as thick as the plates to be used and provided with holding devices or pins on their inner or adjacent faces and with suitable supports adjacent the bottom on which the plates rest, these sides being preferably connected by spacing members or rods which to minimize shrinkage may be formed of metal which may be coated or covered with suitable inert material. The tops and bottoms of the frames are also preferably given a suitable tapered or wedge shape, so that each of the frames 30 can be more readily inserted in tanks or the like and space itself therein with reference to the other frames without requiring the usual guide in the tanks.

In the accompanying drawings showing 40 in a somewhat diagrammatic way an illustrative embodiment of this invention: Figure 1 is a side elevation of a frame. Fig. 2 is a transverse section thereof showing a plate arranged in the frame. Fig. 3 is a small 45 scale diagrammatic section showing a tank and frames therein; and Fig. 4 is an enlarged transverse section through a modified side member.

The tank 1 of any suitable material may 50 have the two supporting shelves or ribs 2 arranged therein and be supported by a shaft or rocking pivots 3 so as to be oscillated during the developing operation and cause the desired agitation of the developer 4 in the tank. By having the axis of oscillation of the tank considerably outside the body of the liquid preferably a number of inches above the same, the liquid is moved or agitated with respect to the plates throughout its entire volume and more desirable uniform developing action is secured. 60

The frames in which the glass plates are mounted during development may with advantage be made of celluloid or other suitable inert tough material and may preferably comprise the sides 5 about three times as thick as the plates and having adjacent the bottom a suitable projection or support, such as 6, preferably so arranged as to engage only the extreme corner of the plate 70 and hold it in position without coming into engagement with the body of the plate so as to have undesirable contact therewith. The sides which are preferably located outside the lateral edges of the plates may also be 75 formed adjacent the top with a suspending member or shoulder, such as 7, for engagement with the supporting shelf or ledge 2 of the tank which holds the plates and holders in proper relative position. These sides 80 may be conveniently spaced apart by spacing rods or members, such as 8, 9, preferably of considerable rigidity, such as metal rods of brass or the like, which may be firmly secured as by being embedded in the ends of 85 the side members which may for this purpose be given extra width at these points of connection, the ends of the rods preferably projecting into but not completely through the side members. 90

The rods may if desired be coated or covered with suitable inert material such as a coating or sheath of celluloid or celluloid varnish, for instance. The rods may be conveniently covered by slipping them into a thin sheath or protecting tube such as 10, of celluloid which may be sufficiently heated to be forced into close engagement with the rod and may be tightly secured by pyroxylin cement to the celluloid sides of the frame so as to prevent any undesirable contact between the developer and the metal at this joint. By making the bottom ends of the side members of tapering or wedge shaped form, such as shown at 11, they may be more readily inserted into the tank and this is also facilitated by providing similar wedge shaped or tapered portions 12 at the top of the frames. The frames may thus be inserted or withdrawn from the tank and moved 100 105 110

or pushed together therein very readily without danger of disturbing the plates if they are properly supported in the frames and there is no substantial danger of locking 5 or wedging the frames in the tanks 1, since the frames are preferably provided with co-operating side members of sufficient width and vertical extent to give ample bearing surface to space the plates apart under these 10 conditions and also when the frames are piled together or arranged in contact for draining or other purposes. Frames adapted for use with plates of about 10x12 inch size may have sides which have a thickness 15 of about three eighths or half an inch and a width of about three-quarters of an inch or so while the extreme width at the top of the side where the projecting suspending shoulder is formed may be as much as an 20 inch and a half or so, although it is of course understood that these co-operating contact members need not extend throughout the entire vertical extent of the sides in all cases. The thickness of the frames is of 25 course preferably made ample so as to project at least an eighth or a quarter of an inch or so beyond the one or two plates which are intended to be supported centrally in each frame, it being usually desirable to 30 have the side members at least several times as thick as the plates to be used.

The plates may be supported in the frames by any suitable holding devices, such as notches or pins and if desired projecting 35 holding pins may be used to definitely support one or more plates in approximately central position in each of the frames and enable them to be readily inserted or withdrawn therefrom. For this purpose suitable pins of celluloid or other inert material may be arranged to project from the inner faces of the side members and the lower holding pins 14 may with advantage 40 be arranged an inch or so above the supporting member 6 for plates of 10x12 inch size, for example. The sets of pins 15 which are arranged an inch or two above the lower pins and the two upper pins 16, 45 17 on each side member are arranged on either side of its central line so as to 50 cooperate with both sides of the plates 18 and the upper pins may be located about the same distance below the upper end of the smallest plate which is to be used in connection with the frame. In this way the 55 plate is so supported that it is practically impossible to displace it accidentally except when the frame is turned upside down and yet when the plate is raised about an 60 inch from the supports adjacent the bottom of the frame its lower end may be readily swung out sidewise over the lower pins 14 so as to entirely release it from the holding devices since the two middle sets of pins 65 are on the same side of the plate. The

upper spacing rods serve as handles for inserting or withdrawing the loaded frames from the various developing tanks and for handling them during the draining or drying operations. These spacing rods firmly 70 support the tough and more or less flexible sides in proper relative position so that warping and distortion as well as accidental breakage is minimized. The width of the frames between the sides is preferably made 75 somewhat greater than the width of the plates as shown in Fig. 1 so that drainage and drying are thus promoted, the holding pins preferably projecting only slightly beyond the edges of the plates and the supports for the lower ends of the plates preferably 80 only engaging the corners for this reason. For this reason it is also desirable in some cases to have the adjacent sides of the holding pins inclined with respect to 85 the plates to be supported, and this may be effected by bending or inclining the projecting portions of the pins as by forming all the pins with conical holding portions as shown in connection with the pins 19, 20 90 in Fig. 4 which minimize their extent of contact with the plates.

This invention has been described in connection with a number of illustrative embodiments, forms, proportions, sizes, arrangements, materials and methods of construction, to the details of which disclosure the invention is not of course to be limited, 95 since

What is claimed as new and what is desired to be secured by Letters Patent is set forth in the appended claims.

I claim—

1. In photographic developing apparatus, a movable developing tank having an oscillating axis above the normal liquid level therein and provided with a celluloid inner surface and supporting shelves on the sides of the tank adjacent the top thereof, developing frames having wide sides formed 105 of celluloid provided with outwardly projecting suspending shoulders adjacent the top thereof to co-operate with said supporting shelves in the tank and provided with inwardly projecting supports for the plates 110 adjacent the bottom of said sides, metallic spacing rods having ends embedded in the enlarged top and bottom ends of said sides to rigidly fasten the members together, a protecting covering of celluloid arranged 115 over the exposed portion of said rods and plate holding devices on the co-operating inner faces of said sides and comprising celluloid holding pins embedded in said sides and arranged on both sides of the plate, 120 there being separated holding pins adjacent the bottom of the sides to promote convenient disengagement of the plates.

2. In photographic developing apparatus, a movable developing tank provided with 130

supporting shelves on the sides of the tank adjacent the top thereof, developing frames having wide sides formed of celluloid provided with outwardly projecting suspending shoulders adjacent the top thereof to coöperate with said supporting shelves in the tank and provided with inwardly projecting supports for the plates adjacent the bottom of said sides, metallic spacing rods having ends embedded in the enlarged top and bottom ends of said sides to rigidly fasten the members together, a protecting covering of celluloid arranged over the exposed portion of said rods and plate holding devices on the coöperating inner faces of said sides.

3. In photographic developing apparatus, a plate developing frame having side members formed of wide strips of celluloid provided with outwardly projecting suspending shoulders adjacent the top thereof adapted to coöperate with supporting members and provided with inwardly projecting supports for the plates adjacent the bottom of said side members, metallic spacing rods having ends embedded in the enlarged top and bottom ends of said side members to rigidly fasten the frame members together, a protecting tubular shield of celluloid arranged over the exposed portion of each of said rods and plate holding devices on the coöperating inner faces of said side members and comprising celluloid holding pins embedded in said side members and arranged on both sides of the center line of said side members to coöperate with opposite faces of the plate, there being separated holding pins adjacent the bottom of the side members to promote convenient disengagement of the plate.

4. In photographic developing apparatus, a plate developing frame having side members formed of wide strips of celluloid provided with outwardly projecting suspending shoulders adjacent the top thereof adapted to coöperate with supporting members and provided with inwardly projecting supports for the plates adjacent the bottom of said side members, metallic spacing rods having ends embedded in the enlarged top and bottom ends of said side members to rigidly fasten the frame members together and plate holding devices on the coöperating inner faces of said side members and comprising celluloid holding pins embedded in said side members and arranged on both sides of the center line of said side members to coöperate with opposite faces of the plate.

5. In photographic developing apparatus, a plate developing frame having side members formed of wide strips of inert tough material provided with outwardly projecting suspending members adjacent the top thereof adapted to coöperate with supporting shelves in tanks and provided with in-

wardly projecting supports for the plates adjacent the bottom of said members, metallic spacing rods secured to the enlarged top and bottom ends of said side members to rigidly fasten the frame members together, an inert protecting covering arranged over the exposed portion of each of said rods and plate holding devices on the coöperating faces of said side members and comprising celluloid holding pins embedded in said side members and arranged on both sides of the center line of said side members to coöperate with opposite faces of the plate, there being holding pins adjacent the bottom of the side members to promote convenient disengagement of the plate.

6. In photographic developing apparatus, a plate developing frame having side members formed of wide strips of inert tough material provided with outwardly projecting suspending members adjacent the top thereof adapted to coöperate with supporting shelves in tanks and provided with inwardly projecting supports for the plates adjacent the bottom of said side members, spacing rods secured to the top and bottom ends of said side members to rigidly fasten the frame members together, an inert protecting covering arranged over the exposed portion of each of said rods and plate holding devices on the coöperating faces of said side members.

7. In photographic developing apparatus, a plate developing frame having side members at least several times as thick as the plates to be used therein and formed of wide strips of inert tough material provided with outwardly projecting suspending members adapted to coöperate with supporting shelves in tanks and provided with inwardly projecting supports for the plates adjacent the bottom of said side members, spacing rods secured to the top and bottom ends of said side members to rigidly fasten the frame members together and plate holding devices on the coöperating faces of said side members.

8. In photographic developing apparatus, a plate developing frame having substantially its entire exposed surface formed of celluloid material and having both its lateral faces substantially flat adjacent the sides of the frame, the upper and lower portions of said frame being tapered inward from said lateral faces to promote separating wedging action, suspending members on the sides of the frame and plate holding devices on the frame to removably support a plate in position recessed within said lateral faces, said frame comprising side members and coöperating spacing members connecting said side members.

9. In photographic developing apparatus, a plate developing frame at least several times as thick as the plates to be used there-

in and having substantially its entire exposed surface formed of celluloid material and having both its lateral faces substantially flat adjacent the sides of the frame, the lower portions of said frame being tapered inward from said lateral faces to promote separating wedging action, suspending members on the sides of the frame and plate holding devices on the frame to 10 removably support a plate in position recessed within said lateral faces.

10. In photographic developing apparatus, a plate developing frame having substantially its entire exposed surface formed 15 of non-absorbent inert tough material and having both its lateral faces substantially flat adjacent the sides of the frame, the upper and lower portions of said frame being tapered inward from said lateral faces to 20 promote separating wedging action, suspending members on the sides of the frame and plate holding devices on the frame to removably support a plate in position inside the plane of said lateral faces, said frame 25 comprising side members and coöperating spacing members connecting said side members.

11. In photographic developing apparatus, a plate developing frame having substantially 30 its entire exposed surface formed of non-absorbent inert tough material and having both its lateral faces substantially flat adjacent the sides of the frame, the upper and lower portions of said frame being 35 tapered inward from said lateral faces to promote separating wedging action, suspending members on the sides of the frame and plate holding devices on the frame to removably support a plate in position inside 40 the plane of said lateral faces, said frame comprising side members and coöperating spacing members connecting said side members.

12. In photographic developing apparatus, a plate developing frame having its exposed surface largely formed of non-absorbent inert tough material and having wide 45 side members at least several times as thick as the plates to be used and formed with lateral faces substantially flat adjacent the sides of the frame, the upper and lower portions of said frame being tapered inward from said lateral faces to promote separating 50 wedging action, suspending members on 55 the sides of the frame and plate holding devices on the frame to removably support a plate in position inside the plane of said lateral faces, said frame comprising metallic spacing members connecting said side 60 members.

13. In photographic developing apparatus, a plate developing frame having its exposed surface largely formed of non-absorbent inert tough material and having wide 65 side members at least several times as thick

as the plates to be used and formed with lateral faces substantially flat adjacent the sides of the frame, the lower portions of said frame being tapered inward from said lateral faces to promote separating wedging 70 action, suspending members on the frame and plate holding devices on the frame to removably support a plate in position inside the plane of said lateral faces, said frame comprising spacing members connecting 75 said side members.

14. In photographic developing apparatus, a plate developing frame having its exposed surface largely formed of non-absorbent inert tough material and having wide 80 side members at least several times as thick as the plates to be used and formed with lateral faces substantially flat adjacent the sides of the frame, and plate holding devices on the frame to removably support a plate 85 in position inside the plane of said lateral faces.

15. In photographic developing apparatus, a plate developing frame having its exposed surface largely formed of non-absorbent 90 material and having wide coöperating side members at least several times as thick as the plates to be used and formed with lateral faces substantially flat adjacent the sides of the frame to insure the 95 spacing apart of the plates, the lower portions of said frame being tapered inward to promote separating wedging action, and plate holding devices on the frame to removably support a plate in position inside 100 the plane of said lateral faces.

16. In photographic developing apparatus, a plate developing frame having wide coöperating side members at least several 105 times as thick as the plates to be used and formed with lateral faces substantially flat adjacent the sides of the frame to insure the spacing apart of the plates, and plate holding devices on the frame to removably support a plate in position inside the plane of 110 said lateral faces.

17. In photographic developing apparatus, a plate developing frame having coöperating side members at least several 115 times as thick as the plates to be used to insure the spacing apart of the plates and plate holding devices on the frame to removably support a plate in position inside the plane of said lateral faces.

18. In photographic developing apparatus, a plate developing frame comprising wide side members located outside the lateral edges of the plates and at least several 120 times as thick as the plates to be used to insure the spacing apart of the plates from each other, suspending members on the frame and plate holding devices on the frame to removably support a plate in position inside the flat faces of said side members, said holding devices comprising pins projecting 125 130

from the opposing inner faces of said side members, the lower pins normally being adjacent the bottom of the plates to allow the lower part of the plate to be swung laterally 5 out of the frame when raised above said lower pins.

19. In photographic developing apparatus, a plate developing frame comprising wide side members located outside the lateral edges of the plates and at least several 10 times as thick as the plates to be used to insure the spacing apart of the plates from each other, and plate holding devices on the frame to removably support a plate in position 15 inside the flat faces of said side members, said holding devices comprising pins projecting from the opposing inner faces of said side members.

20. In photographic developing apparatus, a developing frame adapted to support a single plate and comprising coöperating wide side members located beyond the lateral edges of the plates and at least several 25 times as thick as the plates to be used to insure the spacing apart of the plates from each other, and plate holding devices on the frame to removably support a plate in position 30 inside the flat faces of said side members, said holding devices comprising pins projecting from said side members,

the lower pins normally being adjacent the bottom of the plates to allow the lower part of the plate to be swung laterally out of the frame when raised above said lower pins.

21. In photographic developing apparatus, a developing frame adapted to support a single plate and comprising coöperating wide members located beyond the edges of the plates and at least several times as thick as the plates to be used to insure the spacing apart of the plates from each other, and plate holding devices on the frame to removably support a plate in position inside the flat faces of said side members, said holding devices comprising pins projecting 45 from said side members.

22. In photographic developing apparatus, a developing frame adapted to support a single plate and comprising coöperating members located beyond the edges of the plates and at least several times as thick as the plates to be used to insure the spacing apart of the plates from each other, and plate holding devices on the frame to removably support a plate in position inside the 50 faces of said side members.
